UNITED STATES PATENT OFFICE.

EARL A. AVERILL, OF MOUNT VERNON, NEW YORK, ASSIGNOR TO LOCOMOTIVE FEED WATER HEATER COMPANY, OF WILMINGTON, DELAWARE, A CORPORATION OF DELAWARE.

LOCOMOTIVE-FEED-WATER HEATER.

1,308,835.

Specification of Letters Patent.

Patented July 8, 1919.

Application filed April 5, 1918. Serial No. 226,826.

To all whom it may concern:

Be it known that I, EARL A. AVERILL, of Mount Vernon, in the county of Westchester and State of New York, have invented a certain new and useful Improvement in Locomotive-Feed-Water Heaters, of which improvement the following is a specification.

My invention relates, generally, to locomotive feed water heaters of the class or type in which exhaust steam is employed as the heating medium, and, particularly, to constructions of that type which accord, in operative principle, with that set forth in an application for Letters Patent of the United States filed by me under date of January 26, 1918, Ser. No. 213,872. The object of my present invention is to provide an apparatus of the general character of that of my application aforesaid which shall embody simple and reliable means for effecting the delivery of the condensate from the heater to a receptacle in which it is freed from the proportion of lubricating oil which passes into the heater with the exhaust steam.

The improvement claimed is hereinafter fully set forth.

In the accompanying drawings: Figure 1 is a diagrammatic side view of a locomotive engine and tender, illustrating an application of my invention; Fig. 2, a similar front view of the locomotive; Fig. 3, a diagrammatic view of the lower forward portion of the locomotive, with cylinder and valve chest removed; Fig. 4, a vertical central section, on an enlarged scale, through the condensate delivery mechanism; Figs. 5 and 6, horizontal sections, on a further enlarged scale, on the lines $\alpha\alpha$ and yy respectively of Fig. 4, and; Fig. 7, a diagrammatic view, showing a supplemental delivery tank.

My present invention is, similarly to that of my application Ser. No. 213,872 aforesaid, designed to enable the entire volume of the condensed steam to be freed from contained lubricating oil and returned to the tender tank, for succeeding supply to the heater and thence to the boiler. It is herein exemplified as applied in connection with a feed water supply and heating system, which, in and of itself, is not claimed as of my present invention, said system comprehending a feed water heater, 1, which may be of any suitable and preferred construction, and which is located near the cylinders,

preferably in front of and below the smoke box A', of a locomotive boiler, A. Feed water is drawn from the tender tank, B, through a supply pipe, 2, by a pump, 3, which forces it through a delivery pipe, 4, into and through the heating elements of the heater, 1, which may be of tubular or other known construction of the well known surface type, in which elements it is subjected to the action of exhaust steam, supplied through pipes, 5, and thence passes through a pipe, 6, to and past a check valve, 7, and into the boiler. The condensate of the exhaust steam passes out of the heater through a drain pipe, 8, which, in ordinary practice, drops it upon the tracks.

In the practice of my invention, referring descriptively to the specific embodiment thereof which is herein illustrated, the drain pipe, 8, instead of having, as in ordinary practice, its discharge end open to the track, is extended rearwardly, and is connected to, and forms the supply pipe of, a fluid pressure forcing delivery mechanism, which is inclosed in a delivery tank, 9, said mechanism, which will be presently generally described, being located at any point below the level of the bottom of the heater. A delivery pipe, 10, leads from the forcing mechanism to a filter, 11, of any suitable and preferred construction, which is preferably, as shown, supported on the top of the tender tank, B. A water discharge pipe, 11^a, leads from the filter, into the tender tank, and the oil which is separated from the condensate, in passing through the filter, is withdrawn therefrom through a passage controlled by a cock or valve, 11^b.

The construction of fluid pressure forcing delivery mechanism which is shown in Figs. 4, 5 and 6, is one which is desirably adapted for practical service, and its principal elements comprise a closed delivery tank, 9, with pipe connections to the drain pipe of the heater and to the filter delivery pipe; check valves interposed in said connections; a valvular mechanism for alternately imposing fluid pressure on, and relieving it from, the delivery tank; a float supported on the water of the delivery tank and adapted to actuate the valvular mechanism; and an equalizing reservoir interposed in the line of the heater drain pipe, between the heater and the delivery tank, in which condensate, accumulated during the periods of discharge from the delivery tank, may be retained.

The fluid pressure delivery mechanism illustrated in Figs. 4, 5, and 6, and hereinbefore generally described, is not, in and of itself, claimed as of my present invention, 5 and the same constitutes the subject matter of a divisional application filed by me November 22, 1918, Ser. No. 263,691.

The improvement herein set forth presents the advantages of separating the oil from 10 the condensate of a locomotive feed water heater and preventing the objectionable results of the drainage of condensate upon the track, or escape of uncondensed steam, by an apparatus, the construction of which 15 is simple and inexpensive; which may be readily applied without interference with other members of a locomotive; and which embodies no parts which involve undue cost of maintenance or liability to failure in operation.

I claim as my invention and desire to secure by Letters Patent:

1. In a locomotive feed water heating system, the combination of a feed water heater; 25 a feed water supply receptacle; means for effecting the supply, in separated currents, of feed water and of exhaust steam to the heating elements of the heater; means for separating lubricating material from the 30 condensate of the exhaust steam; a drainage conduit connecting the heater with said separating means; a delivery mechanism, interposed in said conduit, for directly applying fluid pressure to the condensate therein, 35 and thereby forcing it from the conduit to the separating means; and means for delivering the condensate from the separating means to the separating means to the supply receptacle.
2. In a locomotive feed water heating system, the combination of a feed water heater; 40 a feed water supply receptacle; means for effecting the supply, in separated currents, of feed water and of exhaust steam to the heating elements of the heater; means for 45 separating lubricating material from the

condensate of the exhaust steam; a drainage conduit connecting the heater with said separating means; an automatically operable fluid pressure delivery mechanism, interposed in said conduit, for forcing condensate therefrom to the separating means; and means for delivering the condensate from the separating means to the supply receptacle.

3. In a locomotive feed water heating system, the combination of a feed water heater; a feed water supply receptacle; means for effecting the supply, in separated currents, of feed water and of exhaust steam to the heating elements of the heater; means for 60 separating lubricating material from the condensate of the exhaust steam; a drainage conduit connecting the heater with said separating means; a fluid pressure delivery mechanism, automatically operable by variations of level of the condensate, for forcing condensate from the conduit to the separating means; and means for delivering the condensate from the separating means to the supply receptacle.

4. In a locomotive feed water heating system, the combination of a feed water heater; a feed water supply receptacle; means for effecting the supply, in separated currents, of feed water and of exhaust steam to the 75 heating elements of the heater; means for separating lubricating material from the condensate of the exhaust steam; a drainage conduit connecting the heater with said separating means; an automatically operable float actuated fluid pressure delivery mechanism, interposed in said conduit, for forcing condensate therefrom to the separating means; and means for delivering the condensate from the separating means to the supply receptacle.

EARL A. AVERILL.
